UNITED STATES PATENT OFFICE

BERNARD E. O'HAGAN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

ELECTRICAL TRANSLATING APPARATUS

Application filed November 20, 1923. Serial No. 675,845.

My invention relates to electrical translating apparatus, and more particularly to electrical relays of the slow acting type.

I will describe two forms of apparatus embodying my invention, and will then point out the novel features thereof in claims.

In the accompanying drawing, Fig. 1 is a view, partly diagrammatic, showing one form of apparatus embodying my invention. Fig. 2 is a view showing a modification of the apparatus shown in Fig. 1, and also embodying my invention.

Similar reference characters refer to similar parts in both views.

Referring first to Fig. 1, the apparatus which is here shown is a relay comprising a contact mechanism B and a motor device A for operating this mechanism. The motor device A comprises a solenoid or electro-magnet 7 surrounding a liquid tight vessel 8 of suitable material such as glass. This vessel contains a fluid 9 of considerable density such as mercury. A plunger 11 of magnetizable material is arranged to enter vessel 8 and float on the mercury 9. When solenoid 7 is energized plunger 11 is caused to move downward against the buoying action of the mercury. The parts are so proportioned that the clearance space 10 between plunger 11 and vessel 8 is comparatively small and it is therefore plain, that when plunger 11 is drawn downward by energization of magnet 7 the displaced mercury must flow through this restricted clearance space and tends therefore

to retard the motion of the plunger. If this plunger is in its lower position and the magnet is de-energized, the plunger is buoyed upward to its original position but this motion is also retarded by the mercury flowing

through the restricted clearance space.

The contact mechanism B comprises a contact bar 1 provided at 2-2 with pivots which are supported with considerable friction in suitable journals not shown in the drawing.

It is therefore clear that the bar 1 will remain in any position to which it is moved until it is positively moved to a different position. This bar carries two contact fingers 14 and 13 separated from the bar by insulation members 14^c and 13^c, respectively, which fingers

are adapted to coact with certain fixed contact members as will be explained hereinafter. Outstanding from the bar 1 is a vertically disposed yoke 3 having an upper leg 4 and a lower leg 5 provided with adjustable screws 6 and 6^a respectively. The plunger 11 is provided with a plunger rod 12 the free end of which is intermediate the legs of yoke 3 and is adapted at times to engage screws 6 or 6^a.

When plunger 11 is in its upper position, as when magnet 7 is de-energized, plunger rod 12 engages screw 6 in leg 4, thus holding bar 1 in the position shown wherein contacts 13-13^a and 14-14^a are closed. If, now, magnet 7 becomes energized, plunger 11 will be drawn downward. Due to the mercury timing device however, a considerable interval of time will elapse before the plunger rod engages screw 6^a. During this interval of time no motion of bar 1 takes place and contacts 14-14^a and 13-13^a remain closed. When the plunger rod 12 engages screw 6^a, rod 1 will be swung on its pivots in a counter clockwise direction into a position in which contacts 14-14^a and 13-13^a are open and contact 14-14^b is closed. If magnet 7 then becomes de-energized again, plunger 11, after a time interval, again swings bar 1 back to its original position and closes contacts 13-13^a and 14-14^a. It should be particularly pointed out that when plunger rod 12 is intermediate the screws 6 and 6^a, no contact operation takes place.

The speed of the plunger 11 is determined by the clearance space 10 and also by the amount of current supplied to the solenoid 7, as well as by the proportioning of the various parts of the apparatus. For a given speed of the plunger, the time interval between contact operations may be varied by adjusting the screws 6 and 6^a.

As shown in the drawing the magnet 7 is controlled by the contact mechanism B, the circuit for this magnet passing from a suitable source of energy such as a battery 15, through wire 16, contact 13-13^a, wire 17, magnet 7, and wires 18 and 19 back to battery 15. As shown in the drawing this contact is closed and plunger 11 is in its upper position.

When the plunger has moved downward into its lower position, contact 13—13^a will open, thus de-energizing the magnet, and the plunger will again rise to its upper position, thereby closing the circuit. It is therefore plain that the device operates continuously.

Relays constructed in accordance with my invention are particularly adapted for, though in no way limited to, use as flasher relays, that is, relays which alternately energize two current consuming devices. As here shown, two current consuming devices such as electric lamps 28 and 29 are controlled by contact mechanism B as follows.

15 When plunger 11 is in its upper position, a circuit is closed from battery 15, through wire 16, contact finger 13, wire 20, contact 14—14^a, wire 21, lamp 29, and wires 22, 23 and 19 back to battery 15, thus lighting lamp 29. When plunger 11 is in its lower position this circuit is broken and lamp 29 is extinguished but lamp 28 is lighted over a circuit which passes from battery 15, through wire 16, contact finger 13, wire 20, 25 contact 14—14^b, wire 24, lamp 28, and wires 25, 23 and 19, back to battery 15. It is clear from the foregoing that as long as magnet 7 is intermittently operated lamps 28 and 29 are alternately energized.

30 Referring now to Fig. 2, contact 13—13^a of contact mechanism B controls an auxiliary relay 31, this relay being energized, when contact 13—13^a is closed by a battery 30. The relay 31 comprises two armature contacts 32 and 33 which control magnet 7 and lamps 28 and 29 in the same manner as before.

Although I have herein shown and described only two forms of apparatus embodying my invention, it is understood that various changes and modifications may be made therein within the scope of the appended claims without departing from the spirit and scope of my invention.

45 Having thus described my invention, what I claim is:

1. In combination, a vessel containing a fluid, a plunger arranged to float in said fluid, means for at times forcing said plunger downwardly in said fluid, and a contact mechanism operated by said plunger through mechanism separate from said fluid.

50 2. A relay comprising a vessel containing a fluid, a plunger arranged to enter said vessel with comparatively small clearance and to float on said fluid, means for at times moving said plunger downwardly into said vessel whereby the fluid is forced upward between the plunger and the vessel, and contact mechanism operated by said plunger through mechanism separate from said fluid.

55 3. A relay comprising a vessel containing a fluid, a plunger arranged to enter said vessel and buoyed to an upper position by said fluid, means for moving said plunger against

the buoyancy of the fluid to a lower position, and a contact mechanism arranged to be operated mechanically by the plunger as the plunger moves into each such position.

4. A relay comprising a vessel containing 70 a fluid, a plunger arranged to enter said vessel and buoyed to an upper position by said fluid, means for moving said plunger against the buoyancy of the fluid to a lower position, and a contact mechanism mechanically operated 75 by said plunger to perform one operation when the plunger is in the upper position and a different operation when the plunger is in the lower position.

5. A relay comprising a vessel containing 80 a fluid, a plunger arranged to enter said vessel and buoyed to an upper position by said fluid, means for moving said plunger against the buoyancy of the fluid to a lower position, and a contact mechanism mechanically operated 85 by said plunger in said upper position and said lower position but not when the plunger is in an intermediate position, said mechanism being operated through means separate from said fluid.

6. A relay comprising a pivoted contact arm, a yoke on said arm having two spaced legs, a solenoid containing a vessel of mercury, a magnetizable plunger arranged to enter said vessel with small clearance and to float on said mercury but to be forced downwardly in said mercury when the solenoid is energized, and adjustable means on the legs of said yoke for engaging said plunger.

7. A relay comprising a contact operating 100 member having two circuit controlling positions and mounted with sufficient friction to remain in whichever of said positions it may occupy, a plunger located in a liquid whereby it is biased to one position, and its movements are retarded, a solenoid for moving said plunger against its bias to another position, and a lost-motion connection between said plunger and said member whereby the member is moved to one circuit controlling 105 position when the plunger completes a movement under the influence of said solenoid and to the other circuit controlling position when the plunger completes a movement under the influence of its biasing force.

In testimony whereof I affix my signature.

BERNARD E. O'HAGAN.
